STOKER FOR FURNACES

Frank V. Monkosky, Lakewood, Ohio, assignor,
by mesne assignments, to Hugh J. Monson,
Cleveland, Ohio, trustee

Application September 29, 1930, Serial No. 484,956

2 Claims. (Cl. 110—114)

This invention relates to a mechanical stoker which is particularly designed for domestic furnaces, although the device is of general application.

5 The main object of the invention is to provide a mechanical stoker of the character described which is efficient and dependable in operation and which consists of few parts which are readily assembled and disassembled and which 10 are well adapted for quantity production at comparatively low cost.

Another object of the invention is to provide 15 a mechanical stoker of the character described having means for feeding fuel into the furnace and a reciprocating fuel spreader in the form of a ram or plow for distributing the fuel about the firebox.

Another object of the invention is to provide 20 a mechanical stoker for furnaces having a reciprocating ram adapted to be moved across the furnace firebox and a fuel feeding means for delivering fuel in front of the ram together with means for varying the path of travel of the ram.

25 Another object of the invention is to provide a stoker of the character described having fuel feeding means and a reciprocating ram together with means controlled by the movement of the ram for obtaining a pulsating draft in the firebox.

30 Another object of the invention is to provide a mechanical stoker of the character described having fuel feeding means and a reciprocating ram together with means for delivering air to the furnace through and about the grate whereby to cool the ram and by so doing the air is heated thereby delivering hot air which is desirable for perfect combustion.

Another object of the invention is to provide 35 a stoker for furnaces of the character described having fuel feeding means and a reciprocating fuel spreading member together with means for delivering air to the furnace in such a manner as to burn the fine fuel in suspension thereby 40 reducing much of the clinker difficulties, and providing more efficient combustion.

Further and more limited objects of the invention will appear as the description proceeds and by reference to the accompanying drawings 45 in which Fig. 1 is a vertical sectional view illustrating the preferred embodiment of my invention; Fig. 2 is a fragmentary vertical sectional view through the conduit through which the fuel and air is delivered; Fig. 3 is a horizontal sec- 50 tional view on the line 3—3 of Fig. 2; Fig. 4 is

a horizontal sectional view on the line 4—4 of Fig. 2; Fig. 5 is a vertical sectional view on the line 5—5 of Fig. 2; Fig. 6 is an end view of the conduit through which the fuel and air are delivered; Fig. 7 is a fragmentary vertical sectional view similar to Fig. 2 disclosing the ram in the forward position; Fig. 8 is a view similar to Fig. 7 disclosing the ram in the position in which it will appear when an attachment is used for reciprocating the ram horizontally 60 across the firebox; Fig. 9 is a perspective view of the attachment which is used to vary the path of movement of the ram; Fig. 10 is a perspective view disclosing the attachment which is used when it is not desired to vary the path of 65 travel of the ram; Fig. 11 is a vertical sectional view of the castings forming the base member; Fig. 12 is a horizontal sectional view on the line 12—12 of Fig. 11; and Fig. 13 is a somewhat 70 diagrammatic view of the circuit and mechanism for stopping the ram in the rearward position.

75 Referring now to the drawings, the stoker consists of a base member which is formed of three castings 1, 2 and 3, which are secured 80 together by suitable bolts and supported on a plurality of legs. The casting 1 is provided with a flared portion 4 adapted to receive a hopper 5 therein. Journaled between the castings 2 and 3 is the horizontally disposed shaft 85 6 on which is non-rotatably secured a worm 7. Non-rotatably secured on one end of the shaft 6 is a pulley 8. Journaled in the castings 2 and 3 is a shaft 9 on which is non-rotatably secured a worm wheel 10 which meshes with and 90 is driven by the worm 7. Non-rotatably secured on the opposite ends of the shaft 9 are disks 12 and 13, the purpose of which will hereinafter appear. The casting 1 is also provided with the flange or shoulder 14 over which is secured a 95 casing or conduit 15 which is shaped as shown most clearly in Fig. 5. Fitting within the outer end of the casing 15 is a casting 16 which is shaped as shown in Figs. 4 and 5 and which is provided with a pair of upstanding ribs or projections 17 and 18. The casting 16 is also provided with a bottom portion 19 which extends rearwardly into the outer casing 15 and is provided with an upstanding boss 20 having a square opening therein. The casting 16 is also provided 100 with a pair of oppositely disposed ribs or projections 21, 21^a.

105 Disposed within the casing 15 is an annular conduit 22, the outer end of which fits within a recess 16^a provided in the casting 16 and the 110

opposite end of which is received in a similarly shaped recess 14^a in the casting 1. Slidably mounted within the conduit 22 is a fuel feeding bar 23 the upper surface of which is serrated as shown at 24. The opposite end of the fuel feeding member 23 extends through an opening provided in a depending boss 1^a formed on the casting 1. Connected with this end of the feeding member is a link or crank 25, one end of which is connected to the bar 23 by means of a bolt 26 and the other end of which is adjustably connected with the disk 12 by means of a bolt 27 and a serrated lug 27^a which engages a serrated portion provided on the disk 12. Fitting within the end of the casting 16 is a reciprocatory ram 28 which is preferably formed of cast iron and is shaped as shown most clearly in Figs. 2, 3 and 4. The ram 28 has a rearwardly projecting portion or shelf 29 and a forwardly extending outwardly tapered nose portion 30. The lower end of the nose portion 30 is provided with a plurality of openings 31. Arranged within the lower portion of the casing 15 is a reciprocatory bar 32 which is preferably square in cross section, and one end of which projects through a similarly shaped opening in a boss 1^b provided on the casting 1. The opposite end of the bar 32 projects through a square opening provided in the boss 20 formed on the casting 16. The bar 32 is pivotally connected to the ram 28 by means of a pin 34. Secured to the opposite end of the bar 32 is a crosshead 35 which projects through an opening 35^a provided in the casting 1. Connected with the crosshead 35 is a crank 36, one end of which is connected with the crosshead by means of a bolt 37 the opposite end of which is connected with the disk 13 by means of a bolt 38. Below the casting 1 and carried thereby is an electric motor 39 from which leads a shaft 40 which connects with and drives a fan 41 also carried by the casting 1. The fan 41 is provided with a conduit 41^a which leads into an opening 41^b provided in the casting 1 and delivers into the outer casing 15. Non-rotatably secured on the shaft 40 is a pulley 42 which drives the pulley 8 through the medium of a belt 43. Rotatably mounted in a recess provided in the ram 28 is a roller 44 which is held in place by a pin 45. Secured between the ribs 17 and 18 on the rearwardly extending portion 19 of the casting 16 is a block 46 which is held in place by bolts 47 and 48. The block 46 is provided with spaced inclined or stepped portions 49 and 50.

When the motor is operated the bar 32 will be reciprocated and the ram 28 will be moved outwardly, the roller 44 rolling down the inclined surface 49 and 50, thus moving the ram to the position shown in Fig. 7. The casting 1 is also provided with a downwardly extending boss or projection 23^a which is disposed in the entrance to the conduit 22 and the bar 23 is provided with an upwardly extending boss or projection 23^b which cooperates with the boss 23^a to crush large particles of fuel as they enter the conduit. The outer end of the casting 16 is adapted to be positioned within an opening in the firebox or furnace, such as the door. The motor is connected in circuit with a thermostat arranged within the building to be heated so that the circuit will be closed when the temperature falls below a predetermined point. This thermostat may be actuated by the temperature in the room to be heated or it may be a pressure actuated

thermostat actuated by the pressure in the heating system of a steam or hot water system.

When the motor is started, the shaft 40 will be driven which operates the fan. The pulley 8 will be driven from the shaft 40 through the medium of the pulley 42 and belt 43. The pulley 8 turns the shaft 6 on which is non-rotatably secured the worm 7 which meshes with and drives the worm wheel 10 and shaft 9 which carry the disks 12 and 13. When the disks 12 and 13 are driven, the feeding bar 23 and rod 32 are reciprocated in opposite directions. The fuel within the hopper 5 will be fed into the tube 22 and thence delivered by the fuel feeding member through the tube into the furnace in front of the ram 28. The reciprocation of the bar 32 will also reciprocate the ram which is pivotally secured thereto, the roller 44 running up and down the inclined portions 49 and 50 to vary the path of movement of the ram. The fuel delivered in front of the ram will be distributed about the firebox by the ram. The fan 41 is also operated by the motor and delivers a blast of air through the conduit 41^a into the casing 15. Due to the reciprocatory movement of the ram, the furnace will receive a pulsating draft, the air passing through and about the ram to cool the same. The furnace will receive a normal draft of air through the conduit 15 and through the openings in the ram when the motor is not in operation. This pulsating draft of air delivered to the furnace causes the fine fuel to be burned in suspension thereby reducing the formation of clinkers in the firebox.

In the winter time and in cold climates, a deep or thick fuel bed is desirable. When a deep fuel bed is desired, the block 46 is removed and replaced by block 46^a which is shown in detail in Fig. 10 and which is of substantially the same thickness throughout its length. With the block 46^a in place, the movement of the ram will be substantially horizontal as shown in Fig. 8. In the spring or fall or in temperate climates where a thick or deep fuel bed is not desired, the block 46 will be used to vary the path of travel of the ram within the furnace and thus materially reduce the consumption of fuel.

It is also desirable that the ram be stopped only in its rearward position as shown in Fig. 1. In Fig. 13 there is disclosed somewhat diagrammatically a circuit and mechanism for causing the ram to be moved to its rearward position regardless of when the room thermostat or temperature control is actuated. This mechanism consists of an insulating disk 52 secured on the shaft so as to rotate therewith and having a metallic portion 53 having a gap 54 therein. Disposed adjacent the disk 52 is a contact device consisting of a pair of resilient contact arms 55 and 56 which bear against the metallic surface 53. The reference character 57 designates a switch which may be a thermostatic switch actuated by the temperature in the room to be heated or by the pressure in the heating system. When the switch 57 is closed, current will be supplied to the motor from the line through wire 58, motor 39, wires 59 and 60, terminal 61, switch 57, wire 62, wire 63 to the opposite side of the line. Should the switch 57 be opened with the parts in the position shown in Fig. 13, current will flow from one side of the line through the motor, wire 57 and thence through wire 64, contact 65, arm 56, metallic

portion 53, arm 55, contact 66, wire 67, wire 63 to the opposite side of the line; and the motor will continue in operation until the resilient arms 55 and 56 are moved over the gap 54 whereupon the circuit to the motor will be broken until the switch 57 is again closed. The gap 54 is so disposed that the motor will be stopped only when the grate occupies the position shown in Fig. 1. In this position, the furnace 10 will receive normal draft through conduit 15. As the fuel feeding member and fuel spreading member move in opposite directions, it will also be seen that when the motor is turned off, the limit switch will function to stop the parts 15 in such position that the fuel feeder will be just at the beginning of its free stroke which permits the motor to gather momentum before the fuel feeder will reach a position where the fuel will be crushed thereby.

20 It will now be clear that I have provided a mechanical stoker which will accomplish the objects of the invention as hereinbefore stated. Various changes may be made in the shape and size of the parts as well as in the manner of 25 arranging and securing the various parts in place. It is therefore to be understood that the embodiment of the invention herein disclosed is merely illustrative and not to be considered in a limiting sense as the invention is 30 limited only in accordance with the scope of the appended claims.

Having thus described my invention, what I claim is:

1. A mechanical stoker comprising a base 35 member, a fuel delivery conduit leading from said base member and means for delivering fuel thereto, a reciprocatory fuel feeding mem-

ber arranged within said conduit, a second conduit, a reciprocatory fuel spreading member arranged within and adapted to be projected beyond the delivery end thereof, an electric motor for reciprocating said fuel feeding and spreading members, a fan operated by said motor and connected to deliver a draft of air through said second conduit and around said fuel spreading member, said fuel spreading member having a portion extending downwardly below the path of a major portion of the air passing through said second conduit and directing such air downwardly when in advanced position.

2. A mechanical stoker comprising a base member, a fuel delivery conduit leading from said base member and means for delivering fuel thereto, a reciprocatory fuel feeding and crushing member arranged within said conduit, a second conduit, a reciprocatory fuel spreading member arranged within and adapted to be projected beyond the delivery end thereof, an electric motor for reciprocating said fuel feeding and spreading members, a fan operated by said motor and connected to deliver a draft of air through said second conduit and around said fuel spreading member, said fuel spreading member having a portion extending downwardly below the path of a major portion of the air passing through said second conduit and directing such air downwardly when in advanced position, and a limit switch for causing said fuel feeding and crushing member to be stopped only in a fully retracted position.
